UNITED STATES PATENT OFFICE.

ALMON L. CONKLIN, OF SPRING VALLEY, MINNESOTA.

RIVET-RECEPTACLE.

SPECIFICATION forming part of Letters Patent No. 357,177, dated February 8, 1887.

Application filed October 25, 1886. Serial No. 217,196. (No model.)

To all whom it may concern:

Be it known that I, ALMON L. CONKLIN, a citizen of the United States, residing at Spring Valley, in the county of Fillmore and State of Minnesota, have invented new and useful Improvements in Rivet-Receptacles, of which the following is a specification.

My invention relates to improvements in rivet-receptacles; and it consists of the peculiar combination and novel construction and arrangement of the various parts for service, substantially as hereinafter fully described, and particularly pointed out in the claims.

The object of my present improvement is to provide an improved case or receptacle for the storage of rivets or other articles of varying sizes which shall be small and compact in the arrangement of parts and permit of ready and free access to any of the numerous receptacles in order to remove the contents thereof.

A further object of my invention is to provide a rivet-receptacle of the class named which shall permit of the ready filling of either one of the compartments with a rivet of a given size, and effectually prevent the rivets of one size, while filling the compartment provided therefor, from entering the compartments adjacent thereto of rivets of different sizes; and, finally, the object of my invention is to provide an improved receptacle for the uses named which shall possess superior advantages in points of simplicity and strength of construction and cheapness of manufacture.

In the accompanying drawings, which illustrate a rivet-receptacle embodying my invention, Figure 1 is a side elevation. Fig. 2 is a vertical central sectional view on the line $x-x$ of Fig. 1, and Fig. 3 is a transverse horizontal sectional view on the line $y-y$ of Fig. 2.

Referring to the drawings, in which like letters of reference denote corresponding parts in all the figures, A designates a hollow inclosing shell or casing, which is preferably cylindrical in form. This casing is provided with an open bottom and an inwardly-inclined flange or rim, a , at its lower open end. A tubular hollow spindle or shaft, B, extends centrally through the inclosing case or shell, and to the upper end of this spindle is rigidly affixed a transverse handle, b , of any suitable

or preferred pattern, the inclosing case or shell being rigidly connected by the means presently described with the central spindle, so that the entire case can be very easily and readily carried by one hand.

D designates a series of vertical partitions or walls, which are arranged at an angle to each other and radiate outwardly from the central spindle to the inclosing shell or case A. The edges of these partitions or walls are rigidly affixed to the central spindle and to the inclosing-shell, to firmly and securely connect the spindle and shell together, and these partitions are arranged equidistant around the shell or case to form or provide a series of compartments or chambers, D', of equal size or area, in which the rivets of different sizes, or other suitable substances, are stored.

The upper end of the inclosing shell or case A is closed by an inverted cone-shaped cap, E, which is rigidly affixed at its lower edges to the upper edge of the shell or casing, and through the apex or center of which passes the central spindle of the receptacle, the handle thereof being arranged above or exterior to the case and its cap. This cap is provided with a series of openings, e, around or near its edge, which correspond in number with the series of chambers or compartments D' for the storage of the contents of the case, one of these apertures opening into the upper end of each of the said compartments D'.

The cap and the openings therein of the case or shell A are concealed by another cap, F, which, however, is capable of rotary motion upon the fixed cap. This rotary cap F is also in the form of an inverted cone, and at its apex it has a transverse opening, through which the central spindle of the receptacle loosely passes, the said spindle having a flange or collar, f, which surrounds the aperture in the apex of the rotary cap. This cap is provided near its lower edge with an opening, f', of a size and form corresponding to the openings e in the fixed cap E, and the opening f' is adapted to register or coincide with the openings e, to adapt the rivets to pass through the said aligned openings into the chambers or compartments D' of the receptacle. The opening f' in the rotary cap is surrounded by a funnel-shaped spout, F', which is rigidly

affixed to the rotary cap, and thereby moves therewith, and this spout serves to conduct the rivets into the opening f' and prevent them from spilling or escaping.

5 It will be seen that when the opening f' of the rotary cap aligns with one of the openings e in the fixed cap the remaining openings therein are all concealed or hid from view, as well as the cap itself, and by this means the 10 contents of the compartments are prevented from escaping from the upper end thereof, and rivets of a given size are prevented from falling into other than their proper compartments when the rotary cap has been adjusted to cause 15 the spout to open into the same, as will be very readily understood.

G designates a series of radial trays, which correspond in number to the number of compartments or chambers D' of the receptacle.

20 These trays are arranged beneath the open lower ends of the compartments D', so as to receive the contents of the compartments, the sides of the trays being vertical and converged toward the center of the shell, so that 25 they lie in the same vertical plane as the partitions D, which form the chambers D', as is obvious. The trays are thus made larger at their outer ends than at their inner ends, and the enlarged outer ends of the series of

30 trays are extended or projected beyond the vertical shell or case A, as shown, so that the workman can very easily and readily remove one or more rivets from either one of the trays without hindrance from the shell or case

35 A. The bottoms of the trays are inclined or slanted downwardly and outwardly from the central spindle of the receptacle to beyond the vertical inclosing-shell A, so as to cause the rivets falling thereon from the compartments to drop into the outer wider portion of the tray beyond the shell, which is left open, so that free access can be had thereto. The 40 outer wider ends of the trays are closed by vertically-disposed walls g, which are preferably arranged or formed in the arc of a circle to impart a scalloped edge to the series of trays, and thereby prevent the escape of the rivets from the outer end of the trays. The trays are rigidly affixed to the case and to the

45 various partitions D thereof, so that they will move or turn with the case, and thereby cause the trays to always occupy the same relative positions to the compartments.

H designates a base, which is made cylindrical in form and hollow, and this base has the lower end of the spindle B connected thereto in a loose manner, so that the shell and its attached trays can rotate without affecting the base, which is further held against rotary 55 movement or displacement by means of depending spurs or teeth h on the lower under side thereof, which are adapted to enter the wood of the work-bench or other structure, as will be very readily understood. One side of 60 this hollow base is left open, through which a drawer, H', is free to slide. This drawer is provided with a suitable knob or handle for

its convenient manipulation, and is adapted to contain suitable implements for setting the burrs, one of the compartments and trays of 70 the receptacle being devoted to nuts or burrs, which are frequently used by workmen.

The operation of my invention is obvious. The chambers or compartments are successively filled with rivets of different sizes by 75 adjusting the rotary shell so that the spout thereof opens into the upper end of the compartments one after another. The contents of the compartments fall through the open end thereof upon the trays, and they are then deflected toward the outer open end by the inclined bottoms of the trays. The receptacle is placed upon a bench or other structure in convenient reach of the tinsmith or other artisan, and the rivets can be removed from the 85 trays one or more at a time, as may be required. The shell or case can be rotated by merely turning the handle of the central spindle in order to bring the tray of a rivet of a given size into convenient reach of the workman, and without removing the receptacle from the bench, the trays and receptacles revolving simultaneously with the case.

The receptacle can be easily lifted and carried by means of the handle of the central 95 spindle.

My invention is very simple and durable in construction, fulfills a long-felt want among tinsmiths and other workmen who are compelled to use large quantities of rivets in their work, and is cheap and inexpensive of manufacture. I do not, however, wish to confine myself to the use of my invention in any particular art, as I am aware that it can be used to store other substances than rivets.

The compartments or receptacles are stamped or marked to denote the size of the rivets therein.

Having thus fully described my invention, what I claim as new, and desire to secure by 110 Letters Patent, is—

1. The combination, with the rotary casing having the series of compartments and formed with the inwardly-inclined base-flange a, of the open trays having the inclined bottom and the projecting outer portions, as set forth,

2. The combination of the rotary casing having the series of compartments and formed with the inwardly-inclined base-flange a, the open trays having the inclined bottoms and the projecting outer portions, the base, and the central spindle fixed to the casing and pivotally connected to the base at its lower end, as set forth.

3. The combination of the rotary casing having the series of compartments and formed with the inwardly-inclined base-flange a, the open trays having the inclined bottoms and projecting outer portions, the hollow base having the sliding drawer, and the central spindle fixed to the casing and pivotally connected to the base at its lower end, as set forth.

4. A receptacle for rivets and the like, comprising the base H, having the spindle B, and

the shell or case turning by means of the spindle, and having a series of compartments, D, provided with open lower ends, and a series of trays, G, beneath the open ends of each 5 compartment, the outer ends of the trays being extended beyond the compartments to the outside, and open at the tops, and a flange or wall, g, around the outer ends of the trays, as set forth.

10 5. The base H, having points or teeth h, combined with the shell or case turning on a pivot of the base, said shell being divided into a series of compartments provided with open lower ends, a series of trays, G, resting on the 15 base and turning with the shell or case, said trays having open tops and flanged sides and extended beyond the shell or case to the outside, as set forth.

6. The stationary base, the spindle loosely pivoted or swiveled to the base, the receptacle 20 turning with the spindle and provided with the series of compartments open at the top and bottom, and a loosely - turning cap, F, closing the upper open ends of the compartments, and provided with a single spout or 25 hopper to align with the upper open ends of any one of the compartments, said cap F turning with the receptacle, or independently thereof, as desired, as set forth.

In testimony that I claim the foregoing as 30 my own I have hereto affixed my signature in presence of two witnesses.

ALMON L. CONKLIN.
